TREATMENT OF HYDROCARBON OIL

Jacque C. Morrell, Chicago, Ill., assignor to Universal Oil Products Company, Chicago, Ill., a corporation of South Dakota

No Drawing. Application February 18, 1932,
Serial No. 593,877. Renewed April 8, 1935

4 Claims. (Cl. 196—36)

This invention relates more particularly to the refining treatment of the relatively low boiling cracked hydrocarbons produced by the thermal conversion of high boiling hydrocarbon oil mixtures into lower boiling hydrocarbons suitable for use as motor fuel.

In a more specific sense the invention is concerned with an improved process whereby relatively low boiling hydrocarbons may be treated and refined while in heated vaporous condition either as produced from the fractionators of the cracking plant or when the initially produced distillates or naphthas are redistilled to produce end point gasoline.

To produce marketable gasolines from cracked or "pressure" distillates it is practically always necessary to remove all or a major portion of the more highly unsaturated olefinic constituents and also the major portion of the more reactive sulfur compounds, since the former class, even in small percentages, accounts for the gum-forming tendencies of the gasolines and the latter produce the corrosive effects noted upon feed lines, valves, carburetors, et cetera, before the combustion of fuel, and produce oxides of sulfur which cause crankcase corrosion after combustion.

In one specific embodiment the invention comprises the treatment of hydrocarbon oils, particularly cracked hydrocarbon oils, while in heated vaporous condition, with reagent mixtures containing sulfuric and phosphoric acid.

The element phosphorus, owing to its variable valence, forms a considerable number of acids, of which orthophosphoric acid (H_3PO_4) is by far the most common and generally used. This acid is miscible in substantially all proportions with sulfuric acid in various concentrations in which both acids may exist in water. While the invention will be described principally in reference to this most common acid of phosphorus, its scope is not limited thereto but comprises also the use of such other acids of phosphorus as may be suitable when mixed with sulfuric acid under various operating conditions. The following tabulation is appended to show the principal acids of phosphorus with their formulas and commoner properties, such as their melting and decomposing temperatures:

Acids of phosphorus	M. P. °C.	Decomp. at °C.
Orthophosphorous (H_3PO_3)	70	200
Hypophosphorous (H_2PO_2)	26.5	Above M. P.
Hypophosphoric ($H_4P_2O_6$)	55	70
Pyrophosphorous ($H_4P_2O_7$)	38	130
Metaphosphoric ($HPO_3(P_2O_5 \cdot H_2O)$)	Sublimes.	
Pyrophosphoric ($H_4P_2O_7(P_2O_5 \cdot 2H_2O)$)	61	
Orthophosphoric ($H_3PO_4(P_2SO_5 \cdot 3H_2O)$)	38.6	1/2 H ₂ O at 213.

Acid mixtures of the character described may be employed for treating hydrocarbon oil vapors to produce substantially the same refining effects as are ordinarily produced when the condensed vapors are treated with sulfuric acid of commercial grade, neutralized and redistilled with fire and steam to produce gasoline of desired endpoint. By proper selection of the type of phosphorous acid (thus controlling to some extent the oxidizing or reducing effect) and its proper proportioning in respect to the amount and strength of sulfuric acid used in the treating solutions, these effects may be produced upon hydrocarbon vapors over a considerable range of temperatures and pressures, such as, for example, between temperatures of 250 and 600° F. and pressures of from atmospheric to several hundred pounds per square inch. These temperature and pressure ranges will cover in practically all cases the conditions under which vapors of approximate gasoline boiling point range are produced in straight run distilling, re-running or cracking plants. The sulfuric acid apparently has the most pronounced effect upon the vapors, the phosphorous acid acting to some degree as a diluent or spacing reagent, which moderates the intensity of the treating effect of the sulfuric acid, and prevents the decomposing and charring effects usually noted when attempts are made to treat hydrocarbon oil vapors with it at elevated temperatures. The advantage inherent in thus using the phosphorous acid as a diluent for sulphuric acid appears in the lower vapor pressure of the acid, so that the equivalent of dilute aqueous solutions of sulfuric acid may be used with substantially no tendency toward increase in concentration during treatment. However, since the process may be employed under a wide variety of operating conditions as already stated, it may be advantageous or necessary in some cases to add water to the mixture of acids and/or steam to the vapors undergoing treatment to prevent or retard evaporation of whatever water may be present in the solution.

In applying the invention to practice, the optimum proportions and concentrations of sulfuric acid, phosphoric acid and water will be determined best by trial in a majority of instances, since the exact treating effect to be expected when treating vapors of different composition from different sources is not accurately predictable from analytical data.

The solutions may be applied to the vapors in any type of treating equipment capable of effecting intimate contact between liquids and vapors, such types of equipment including vertical cylindrical treating towers containing various types of filling material such as coarse silica fragments, Raschig rings, crushed firebrick, et cetera,

and also similar towers containing regularly spaced trays or baffles. The simplest method of operation is usually to inject the treating solutions into the upper portion of the treating tower 5 through some distributing means such as a spray or atomizer and then allow the liquid to flow downwardly countercurrent to the ascending stream of vapors. In some instances treatments may be conducted with the reagent and vapors 10 flowing in the same direction, in which case any portions of the vapor which may condense will be subjected to liquid phase treatment. The use of a jet mixer is also satisfactory.

The spent reagents mixed with reaction products and some unconverted oil may be drawn from the bottom of the treater continuously or intermittently, the oil separated by gravity and the sludge acids subjected to any necessary regenerating steps to permit their cycling to the 15 treater in lieu of fresh materials.

The invention is not limited to the use of any particular temperature and pressure ranges and, while it may be generally stated that temperatures of from 250 to 600° F. and pressures from 20 atmospheric to several hundred pounds per square inch may be employed, it is further comprised within the scope of the invention to vary pressure and temperature independently either by superheating vapors above the temperatures 25 normal to the pressure under which they exist or to use pressures less than atmospheric so that correspondingly low temperatures are available with corresponding modification of the results obtained by the treatment. In all cases the 30 strength of the treating reagent and the conditions of operation will be chosen that are best suited to the efficient treatment of the vapors in question.

The effects produced upon hydrocarbon oil 35 vapors, particularly cracked vapors, are comparable to those produced by ordinary sulfuric acid treatments, and possess the added virtues of having a more selective action upon the di- and tri-olefins in vapor mixtures and of producing desulfurizing effects without removing unduly large percentages of mono-olefins, which are valuable in gasoline on account of their anti-knock character.

The process may be employed as a single treatment upon hydrocarbon oil vapors, or it may be used as one step in a series of treating steps, both vapor and liquid phase. For example, the vapors may be contacted with fuller's earth, 40 metal oxides, et cetera, prior to the use of the reagents described and treatment may be followed in turn by neutralizing treatments with caustic alkalis and ammonia or light final treatments upon the condensed vapors.

The corrosive effect of the treating mixtures 45 may be overcome by the use of acid-resisting metals or suitable linings. For example, the treating towers may be lined with silicate mixtures and cements involving the use of water glass, fire clay, et cetera, or they may be lined with various enameling compositions.

A single example of results selected from the 50 many made possible by the use of the invention may be given as illustrative of the value of the process. In treating the vapors of approximate gasoline boiling point range arising from a cracking system operating on an approximately equal mixture of California heavy residuum and gas oil distillates as charging stock, a solution con-

taining approximately 40% sulfuric acid, 50% phosphoric acid and 10% water may be employed. The vapors from the high pressure fractionator 5 may be reduced to a pressure of 50 pounds per square inch, at which their mean temperature is in the neighborhood of 325-350° F. These vapors may be passed upwardly through a filled tower containing coarse silica fragments with the solution flowing downwardly by gravity. By using an amount of reagent equal to approximately six 10 pounds per barrel of finished gasoline and following the main treatment by neutralization of various acidic products with gaseous ammonia, the finally rectified gasoline after a light caustic wash may have the properties shown in the column headed "treated gasoline" as compared with a similar boiling range gasoline produced by simple fractionation of the vapors without chemical treatment:

Comparison of untreated and treated gasoline

	Untreated	Treated	
Gravity "A. P. I.	53.5	54.1	25
Endpoint °F.	418	412	
Color—Saybolt....	4	Plus 30	
Color after 4 hours' exposure to sunlight....	Yellow.	25	
Mgs. gum by copper dish method....	260	25	
Total sulfur percent....	0.45	0.14	

The above description and single example of results obtainable by the use of the process will serve to define the novel character of the invention and exemplify its operation and practical value. However, neither the specification nor the figures given in the example are to be considered as imposing undue limitations upon the generally broad scope of the invention.

I claim as my invention:

1. A process for refining cracked hydrocarbon oil of motor fuel boiling range and containing mono- and di- and tri-olefins to remove color and gum forming components and to reduce the sulphur content thereof, which comprises subjecting the hydrocarbon oil while entirely in vapor phase to the action of a mixture of sulphuric and phosphoric acids.

2. A process for refining cracked hydrocarbon oil of motor fuel boiling range and containing mono- and di- and tri-olefins to remove color and gum forming components and to reduce the sulphur content thereof, which comprises subjecting the hydrocarbon oil while entirely in vapor phase to the action of a solution containing sulphuric and phosphoric acids.

3. A process for refining cracked hydrocarbon oil of motor fuel boiling range and containing mono- and di- and tri-olefins to remove color and gum forming components and to reduce the sulphur content thereof, which comprises subjecting the hydrocarbon oil while entirely in vapor phase to the action of an aqueous solution containing sulphuric and phosphoric acids.

4. In the cracking of hydrocarbon oil wherein the cracked products evolved from the oil are fractionated to condense and separate fractions thereof heavier than gasoline, the method which comprises subjecting low boiling products uncondensed by the fractionation, while entirely in vapor phase, to the action of a mixture of sulphuric and phosphoric acids.
